UNITED STATES PATENT OFFICE

162,434

FERRIS WHEEL DISPLAY RACK

Charlie Lee Norton, Jr., Danville, Va., assignor to Dan River Mills, Incorporated, a corporation of Virginia

Application October 20, 1950, Serial No. 12,641

Term of patent 14 years

(Cl. D80—9)

To all whom it may concern:

Be it known that I, Charlie Lee Norton, Jr., a citizen of the United States, residing at Danville, in the county of Pittsylvania and State of Virginia, having invented a new, original, and ornamental Design for a Ferris Wheel Display Rack, of which the following is a specification, reference being had to the accompanying drawing, forming part thereof, in which:

I claim:

The ornamental design for a ferris wheel display rack, substantially as shown and described.

CHARLIE LEE NORTON, JR.
